(57) **CLAIM**

The ornamental design for a sneaker, as shown and described.

DESCRIPTION

FIG. 1 is a front right perspective view of an embodiment of a sneaker showing our new design; FIG. 2 is front view of the design shown in FIG. 1; FIG. 3 is a rear view of the design shown in FIG. 1; FIG. 4 is a right side view of the design shown in FIG. 1; FIG. 5 is a left side view of the design shown in FIG. 1; FIG. 6 is a top view of the design shown in FIG. 1; and, FIG. 7 is a bottom view of the design shown in FIG. 1. The figures include broken and solid lines. The areas within the solid lines form the claimed design. The broken lines are included for the purpose of illustrating environmental structure of the sneaker and form no part of the claimed design. Color forms no part of the claimed design.
